UNITED STATES PATENT OFFICE.

LOUIS STEINBERGER, OF NEW YORK, N. Y.

BUILT-UP INSULATOR.

No. 839,666.

Specification of Letters Patent.

Patented Dec. 25, 1906.

Application filed October 28, 1905. Serial No. 284,794.

To all whom it may concern:

Be it known that I, LOUIS STEINBERGER, a citizen of the United States, and a resident of the city of New York, borough of Brooklyn, in the county of Kings and State of New York, have invented a new and Improved Built-Up Insulator, of which the following is a full, clear, and exact description.

My invention relates to insulators of the kind used for currents of high potential and in which it is desirable to secure the greatest possible dielectric quality combined with a maximum of physical strength and a minimum of materials and weight.

Among the further objects accomplished by my invention I enable the operator to readily take the same partially apart without interrupting the service, so as to examine the interior portions of the insulator for the purpose of cleaning it or for coating the exposed surfaces or to replace the oil used for increasing the insulation.

Reference is to be had to the accompanying drawings, forming a part of this specification, in which similar characters of reference indicate corresponding parts in all the figures.

Figure 1 is a vertical section through my improved insulator, taken upon the line 1 1 of Fig. 2 looking in the direction of the arrow. Fig. 2 is a fragmentary plan view of the insulator, the upper hood being partly broken away and Fig. 3 is a horizontal section upon the line 3 3 of Fig. 1 looking in the direction of the arrow and showing the lower hood encircling the supporting-pin.

A cross-arm is shown at 4, and mounted upon it is a threaded stem 5, of metal, provided with an enlarged portion 6, serving as a base, and also with a threaded portion 7, projecting below the cross-arm 4 and engaged by nuts 8. A sleeve 9, made of metal and threaded internally, is provided externally with steps 10 and is also provided with a head 11, the latter being rounded and integral with the body of the sleeve. Resting upon the head 11 is the lower hood 12, provided with petticoats 13 14 and with annular steps 15 15^a, leading upward from an annular shoulder 15^b. Resting upon the lower hood 12 is a bracing-hood 16, provided with an annular portion 17, adapted to hold oil, as indicated. This bracing-hood 16 terminates at its outer surface in an annular bead 18. The middle hood is shown at 19 and is provided with a petticoat 20 and with an-

nular beads 21 22, between which the annular bead 18 of the bracing-hood 16 projects. The bracing-hood 16 is provided with annular steps 23, integral therewith. The middle hood 19 is further provided with annular steps 19^a 19^b concentric with each other. A bracing-hood 24 is stepped to fit the top of the hood 19, and is adapted to rest thereupon. The bracing-hood 24 is further provided with an annular step 24^a and also with an annular oil-channel 25. The top hood 26 is provided with annular beads 27 28, disposed upon opposite sides of an annular bead 29, which constitutes the extreme outer edge of the bracing-hood 24—that is to say, the annular bead 29 fits intermediate of the annular beads 27 28 and braces a portion of the hood 26. This hood is provided with a petticoat 29 and is further provided with a threaded cylindrical aperture 30, encircling the threaded stem 5. The hood 26 terminates in a head 31, which is provided with a central slot 32 and with an annular slot 33 in the manner well known in the art.

In assembling the insulator the threaded stem 5 may be first mounted upon the cross-arm 4 and secured firmly in position by means of the nuts 8. The threaded sleeve 9 is next secured into position from the top of the stem. The hood 12 is now screwed down until it rests upon the head 11 of the sleeve 9. Next the bracing-hood 16 is screwed into position and this is followed by the middle hood 19 and the bracing-hood 24, these last-mentioned hoods being screwed down in succession. Lastly, the top hood 26 is lifted into position and rested, so that the concentric annular beads 27 28 are upon opposite sides of the annular beads 29, the central portion of the hood 26 meanwhile resting upon the central portions of the bracing-hood 24. If desired, the hoods may be assembled upon the pin before the latter is secured upon the cross-arm. The oil-channels 17 25 are partially filled with oil. This is done preferably after the insulator is partly assembled upon the cross-arm, but may be readily done after the complete assemblage is made. If now the operator desires to examine the oil-channels at any time for the purpose of replenishing the oil or of knowing its condition, he climbs up the cross-arm 24 and turns the threaded sleeve 9 so as to screw the same downward. The lower hood 12 does not move downward immediately, but may be

rotated and thus run downward upon the threaded stem. Similarly the bracing-hood 16 is turned and lowered, the middle hood 19 resting for the time upon the threaded stem 5 and being otherwise unsupported. 5 This hood 19 may in turn be moved downward by rotation, leaving the supporting-hood 24 in its original position, supported by the threaded stem 5. If now the supporting-hood 24 be moved downward by rotation, the upper hood 26 is left resting upon the upper end of the stem. If desired, the several hoods may be so adjusted that the upper hood 26 rests partly upon the upper end of 10 the stem. For this purpose the cylindrical aperture 30 is made of such size so as to loosely encircle the upper end of the stem.

It will be noted that each annular bead 18 and 29 is so fitted into the hood 19 or 26 above it as to make a joint which is practically air and water tight.

It will also be noted that the danger of surface leakage is greatly reduced and that in an insulator built up as above described all parts are readily accessible to the operator no matter what may be the size or carrying capacity of the insulator. A single operator can handle insulators of this type independently of their aggregate weight when in position. For convenience I designate the lower hood 12, the middle hood 19, and the upper hood 26 as "protecting-hoods" in order to distinguish them from the supporting-hoods 16 and 24.

35 It will be noted that my invention enables me to build insulators having hoods of far greater diameter than could possibly be made for practical uses if built without bracing members, and inasmuch as my hoods and 40 bracing members are separable should any of the parts become destroyed they may be readily replaced and the full efficiency of the insulator thus restored.

I do not limit myself to the use of any particular material from which to construct my insulator, but prefer to use "electrose," nor do I limit myself to the particular form nor to the exact construction of any of the parts, as herein shown, nor to the use in every instance of a filling insulating material for the interior of the bracing member, as variations in form and construction will readily occur to those skilled in the art without departing from the scope and spirit of my invention.

55 Having thus described my invention, I claim as new and desire to secure by Letters Patent—

1. An insulator, comprising a protecting-hood provided with a central aperture, a stem disposed partially within said aperture, and a supporting-hood mounted upon said stem and provided with portions engaging said protecting-hood for the purpose of sustaining a portion of the weight thereof.

60 2. A built-up insulator, comprising a plu-

rality of separate protecting-hoods, a plurality of separate supporting-hoods sandwiched intermediate of said protecting-hoods and engaging the same, and a supporting-stem common to all of said hoods.

3. An insulator, comprising a protecting-hood provided with a portion for engaging a stem and also provided with steps, a supporting-hood provided with steps mating those of said protecting-hood, a threaded stem engaging said supporting-hood, and a member mounted upon said stem and engaging said supporting-hood so as to strengthen the same.

4. A built-up insulator, comprising a protecting-hood, a stem for supporting the same, and a sleeve mounted upon said stem and provided with a head engaging a portion of said protecting-hood for the purpose of locking the latter.

80 5. A built-up insulator, comprising a stem provided with a thread, a protecting-hood provided with a thread and screwed upon said stem, and a sleeve provided with a thread and likewise screwed upon said stem, 90 said sleeve being provided with a portion for engaging a portion of said protecting-hood.

6. A built-up insulator, comprising a protecting-hood provided with an aperture, a stem engaging said protecting-hood, and a 95 sleeve mounted upon said stem and provided with a portion disposed within said aperture for the purpose of sustaining a part of the weight of said protecting-hood.

7. An insulator comprising a hood, and a 100 cup-like bracing member supporting the outer portion of said hood, said bracing member having a separate insulating material disposed within its cup-like portion.

8. An insulator, comprising a supporting-stem, a hood mounted thereupon and movable relatively thereto, and a member mounted upon said stem and adjustable in relation thereto, said member being provided with a portion for partially supporting said hood.

9. An insulator, comprising a hood provided with a hollow portion, a supporting-stem, and a member adjustably mounted upon said supporting-stem and provided with a bead engaging said hollow portion.

10. An insulator, comprising a stem, a sleeve mounted thereupon and adjustable relatively thereto, and a hood mounted directly upon said stem and engaging said sleeve so as to be partially supported thereby.

11. An insulator, comprising a stem, a bracing-hood mounted thereupon and provided with a portion extending outwardly, and a hood loosely mounted upon said stem and provided with a portion engaging said outwardly-projecting portion of said bracing-hood.

12. An insulator, comprising a supporting-stem, a hood mounted thereupon, a sleeve mounted upon said stem, and pro-

- vided with a portion for engaging said hood, said sleeve being further provided with steps for preventing surface leakage.
13. An insulator comprising a hood and a cup-like bracing member supporting said hood at a portion spaced from the center thereof and provided with means for retaining oil.
14. An insulator comprising a protecting-hood, a stem connected therewith, a supporting member mounted on said stem and engaging said hood at a point substantially midway between said stem and the outer peripheral edge of said hood.
15. An insulator comprising a plurality of contiguous hoods, and a separate member disposed intermediate of said hoods, said separate member resting upon one of said hoods at a point near the center thereof, and extending outwardly so as to engage the other of said hoods, at a point farther from its center.
16. An insulator comprising a plurality of contiguous hoods and a separate cup-like member resting upon one of said hoods and provided with a cup-like portion adapted to retain oil, and extending obliquely upward so as to engage the other of said hoods at a point substantially midway between its center and its outer peripheral edge.
17. An insulator comprising a stem, a bracing member mounted thereupon and provided with a portion extending obliquely outward and adapted to hold a liquid insulating material, and a hood mounted upon said stem and provided with a portion engaging said extending portion of said bracing member.
18. An insulator comprising a portion provided with an extending hood, and a bracing member mounted below said hood and provided with portions reaching obliquely outward so as to support said hood at a point remote from the center thereof.
19. The combination of a stem, a supporting member mounted thereupon, and a hood loosely engaging said supporting member and held thereupon by its weight only.
20. The combination of a hood provided with an annular bead, a stem for partially supporting said hood, and a supporting member connected with said stem and provided with an annular portion engaging said annular bead.
21. The combination of a hood provided with two annular beads concentric to each other, and a supporting member provided with an annular portion engaging said hood intermediate of said annular beads.
22. The combination of a hood provided with an annular bead, and a hollow member provided with a portion for retaining oil, and further provided with an annular bead engaging said annular bead of said hood.
23. The combination of a threaded stem, a threaded sleeve revolvably mounted thereupon and provided externally with steps, and a hood encircling said stem or engaged by said sleeve, and partially supported thereupon.
24. In an insulator, the combination of a hood mounted thereupon, a sleeve mounted upon said stem and engaging said hood for the purpose of partially supporting the same, said sleeve being provided with steps.
25. The combination of a threaded stem, a supporting member mounted thereupon, and a hood loosely engaging said supporting member and held thereupon by its weight only.
26. An insulator comprising a hood provided with a central body portion, and a cup-like bracing member engaging said body portion, and also engaging said extended portion at a portion intermediate of said body portion and the peripheral edge of said extended portion, and means for mounting said body portion and said cup-like bracing member.
27. An insulator comprising a central portion having an extended portion, and a separate supporting member engaging said central body portion and also engaging said extended portion, the point of engagement with the latter being approximately midway between the center of said body portion and the outer peripheral edge of said extended portion, and means for mounting said body portion and said separate supporting member.
28. An insulator comprising a supporting-stem, a hood engaging the same, a member engaging said stem and provided with an extended portion for directly engaging said hood at a point substantially midway between its center and its peripheral edge.
29. An insulator comprising a supporting-stem, a hood engaging the same, and a member engaging said stem and provided with a portion for partially supporting the said hood.

In testimony whereof I have signed my name to this specification in the presence of two subscribing witnesses.
